US00D772196S

(12) **United States Design Patent** (10) **Patent No.:** **US D772,196 S**
(45) **Date of Patent:** **** Nov. 22, 2016**

(54) **WIRELESS HEADSET**

(71) Applicant: **LG ELECTRONICS INC.**, Seoul (KR)

(72) Inventors: **Eunseok Choi**, Seoul (KR); **Kyubong Choi**, Seoul (KR)

(73) Assignee: **LG ELECTRONICS INC.**, Seoul (KR)

(**) Term: **15 Years**

(21) Appl. No.: **29/534,894**

(22) Filed: **Jul. 31, 2015**

(30) **Foreign Application Priority Data**

Feb. 2, 2015 (KR) 30-2015-0005708

(51) **LOC (10) Cl.** **14-01**

(52) **U.S. Cl.**

USPC **D14/205**

(58) **Field of Classification Search**

(57) **CLAIM**

The ornamental design for wireless headset, as shown and described.

DESCRIPTION

FIG. 1 is a perspective view of a wireless headset showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a reference view thereof showing the state that the earphone part and the main body are detached from each other; and,

FIG. 9 is a reference view thereof showing an example of the usage of the subject design.

The broken lines depict portions of the wireless headset that form no part of the claimed design.

1 Claim, 8 Drawing Sheets
